THERMOSTAT

Charles R. Palmer, Glen Acres, Ohio

Application June 26, 1940, Serial No. 342,510

2 Claims. (Cl. 200—141)

The invention relates to improvements in thermostats employing a capillary tube.

It is an object of the invention to provide a thermostat in the form of a sealed capillary tube, wherein the expansive fluid serves as a conductor, to maintain and control an electric circuit, and adapted at a determined temperature to develop a pressure internal of the tube sufficient to shatter the fluid containing bulb of the tube and forcibly expel the fluid to break or open the electric circuit, thereby requiring tube replacement before the circuit can be re-established.

Another object of the invention is to provide a thermostat in the form of a capillary tube, wherein the expansive fluid is an electric circuit conductor and controlling medium below a predetermined maximum degree of temperature, either internal or external of the tube; the expansion of the fluid at the maximum degree of temperature developing a pressure sufficient to shatter the tube and expel the fluid for an automatic electric circuit cut-off control.

Another object of the invention is to provide a non-variable thermostat in the form of a capillary tube for insertion in an electric circuit to disrupt the circuit at a predetermined degree of temperature, the tube of minimum size, simple and cheap in construction, and as a clip insertable in an electric circuit.

Another object of the invention is to provide a capillary tube thermostat in which the expansive and electro-conductive fluid is opposed by a vapor head pressure for shattering the tube and expelling the fluid by an excessive pressure developed at a determined degree of temperature.

It is a further object to constrict the bore of the tube near the egress end thereof and preferably intermediate the contacts to decrease the velocity of the flow of the mercury during its expulsion to effectively clear said end of the tube and a portion thereof between the contacts of all mercury to assure complete disconnection of the contacts.

Various other features and advantages of the invention will be more fully apparent from a description of the accompanying drawing, in which:

Figure 1 is a side elevation of the thermostat or electric circuit breaker in a mounted position and in an electric circuit.

Figure 2 is a central vertical section taken on line 2—2, Figure 1.

Figure 3 is a view similar to Figure 2, with the

lower bulb portion of the tube shattered, and the electro-conducting expansive fluid expelled.

Figure 4 is a cross sectional view taken on the line 4—4, Figure 1.

Figure 5 is an enlarged cross sectional detail view, taken on line 5—5, Figure 2.

The thermostat in the present instance is in the form of a tube 10 of glass or other insulating material, provided with a capillary bore 11 closed at one end, and at the other end connecting with the interior of the bulb 12, integral with the tube. The wall of the bulb is preferably thinner than the wall of the tube, so that upon excess pressure in the tube the bulb will be the first to rupture.

Intermediate its ends, the bore 11 is provided with a constriction 13. Contacts 14, 15, provided in spaced relation in the bore at each side of the constriction 13 are formed by the inwardly projecting ends of wires passing through and sealed in the wall of the tube. The contacts are normally connected by a column of electrical conductive fluent material, such as mercury, in the bore 11 and bulb 12. For all normal temperatures, the upper end of the mercury column is spaced from the upper end of the tube, as shown at 16.

The mercury is under a head pressure in the tube at normal temperature, the pressure being produced by a quantity of compressible vapor such as nitrogen gas, trapped in the bore between the upper end of the column of mercury and the closed upper end of the tube. The gas trapped above the column is under pressure, representing the compression of a volume of gas that when free will more than fill the bore of the tube and the interior of the bulb.

To obtain this pressure, the gas may be introduced into the tube under pressure through its upper end, while the mercury in the bulb is cooled and the open end of the tube then sealed. Subsequently, upon the temperature of the mercury coming up to normal, the mercury rises in the tube, additionally compressing the gas. Rise of the mercury column due to temperature changes of the mercury, occasioned by normal atmospheric variations, are permitted by the space normally between the upper end of the column and the end of the tube.

Metal clips 17 for supporting the tube, are clamped in spaced relation to the tube by screws and nuts 18, and have outwardly extending portions which are secured by screws 19, to an insulating mounting block 20, located at a point where an indication of temperature change is desired. The clips are connected electrically with

the contacts 14, 15, in the bore of the tube, the wires of the contacts respectively clamped between the clips and the wall of the tube. Opposite lines of the circuit in which the thermostat is placed are connected to the clips with the lines clamped under the heads of the screws 19.

The tube may be located at any point where it is desired to have an indication of an abnormal predetermined rise in temperature, being placed, for instance, in a room of a building and connected in an electric circuit to break the circuit and cause an alarm to be sounded in case of fire.

When the temperature in the neighborhood of the tube rises to the predetermined degree, the mercury expands, decreasing the volume of the trapped gas, and increasing its pressure to a value that ruptures the bulb. The mercury is forcibly expelled from the tube by expansion of the gas trapped at the top of the mercury column, clearing the tube of mercury and disconnecting the contacts 14, 15. The flow of the mercury through the tube is decelerated by the constriction 13 in the bore of the tube as the mercury passes the constriction. The constriction retards the mercury from a too rapid discharge, and thereby prevents the creation of a partial vacuum in the bore, which would draw the mercury back into the bore and possibly effect a bridging of the electric circuit terminals 14 and 15.

The use of pressure to expel the mercury from the thermostat makes it possible to use a tube having an exceedingly small bore, requiring a minute quantity of mercury, and providing economy, especially since the mercury is lost upon operation. The forceful expulsion of the mercury upon rupture of the bulb assures a quick positive break of the circuit, preventing arcing, the expanding gas effectively driving out the mercury.

The gas pressure in the capillary bore permits the thermostat to be placed in an inclined or inverted position without disturbing the mercury column or effecting operation of the thermostat. It also prevents parting of the column and guards against breaking of the circuit except when the ambient temperature reaches the predetermined value.

The thermostat as a capillary tube has a bulb or more fragile end capable of being shattered by a determined degree of pressure within the bore of the tube developed by the movement of the thermo-expansive fluid within the bore at a determined degree of temperature to expel the fluid from the tube to control an electric circuit.

The tube is of miniature size and inexpensive to manufacture, so that its replacement, which is required to re-establish the electric circuit, can be made at a very nominal cost.

5 The thermostat is constant in maintaining the electric circuit at any temperature below a maximum degree, and its column height normally is not altered to uncover either of a pair of contacts for an interruption of the circuit, and therefore also may be used or inserted in an electric circuit to serve as a fuse.

Having described my invention, I claim:

1. A thermostat, comprising: a sealed capillary tube having a bulb at one end of a fragility to rupture upon the development of a predetermined pressure in the bore of the tube, a thermo-expansive electro-conductive fluid contained in said bulb and rising in a column in the bore of the tube, a pair of spaced electrodes traversing the tube and in constant electric-conductive connection through the fluid in said bore under abnormal low degree thermo-conditions for maintaining an electric circuit, the head end of the bore of the tube supplied with a vapor under pressure and compressive by the rise of the fluid column thermally to a determined height to develop a pressure for rupturing the bulb and expel the fluid from the bore for breaking the circuit between the electrodes, the bore of the tube between the electrodes constricted for a control of the expulsion of the fluid when the bulb is ruptured to assure a complete discharge thereof between the electrodes.

2. A thermostat, comprising a capillary tube having a bulb at one end thereof in communication with the bore of the tube, a thermo-expansive electro-conductive fluid in said bulb and extended to a determined column height in the bore of the tube, the bulb of a fragility to be ruptured by a determined degree of pressure developed upon expansion of the fluid column compressing a vapor charge supplied in the bore over the head end of the fluid column upon exposure of the tube to a determined degree of temperature, the bore constricted in proximity to the bulb and electric circuit electrodes extending within the tube respectively relatively disposed beyond opposite ends of the bore constriction, and normally exposed to the thermo-expansive fluid to complete an electric circuit, the constriction providing for an electric circuit interrupting discharge of the thermo-expansive fluid upon rupture of the tube bulb.

CHARLES R. PALMER.
